UNITED STATES PATENT OFFICE.

WILLIAM F. HUTCHINSON, OF NEW YORK, N. Y.

STAVE-MACHINE.

SPECIFICATION forming part of Letters Patent No. 544,539, dated August 13, 1895.

Application filed April 6, 1895. Serial No. 544,704. (No model.)

To all whom it may concern:

Be it known that I, WILLIAM F. HUTCHINSON, of the city, county, and State of New York, have invented new and useful Improvements in Stave-Machines, of which the following is a full, clear, and exact description.

My invention relates to improvements in a machine for and method of converting a strip of veneer into staves. It is well known that veneer turned from a rotary veneer-machine is very smooth, and it is also understood by those familiar with veneers that any necessary grooves may be turned in the veneer as it comes from the machine, and that its edges may be beveled, if desired. In consonance with this idea my invention contemplates turning a strip of veneer from a log, with the croze-grooves in the strip and with the edges of the veneer beveled, and then passing the strip through a machine which will cut the strip of veneer crosswise, thus forming it into a series of staves, the length of which corresponds to the width of the veneer strip, and at the same time giving to the staves the necessary end taper. It will be observed that the grain of the individual staves will thus run lengthwise of the staves; that the staves will be shaped ready for use and will be to all intents like an ordinary shaved stave.

The object of my invention is to produce a very simple, durable, and efficient machine, which is adapted to rapidly cut a strip of veneer of the kind described into staves, which has a series of rotating knives arranged on a revoluble cutting-drum to cut the veneer, and which has a carrier serving also as an ejector and adapted to feed the veneer to the machine and carry away and deposit the formed staves.

A further object of my invention is to provide simple and efficient means for ejecting the waste material which is cut between the tapered ends of the staves, and in general to provide for the quick conversion of the veneer strip into staves.

To these ends my invention consists of a method and machine which will be herein-after described and claimed.

Reference is to be had to the accompanying drawings, forming a part of this specification, in which similar figures of reference indicate corresponding parts in all the views.

Figure 1 is a broken side elevation, partly in section, of the machine embodying my invention. Fig. 2 is a central vertical cross-section of the machine. Fig. 3 is an enlarged detail longitudinal view of one end portion of the cutting-drum and of the mechanism for ejecting the waste material from between the knives thereof. Fig. 4 is a broken rear elevation of the machine. Fig. 5 is an enlarged detail sectional view of the brush device used in connection with the ejecting mechanism shown in Fig. 3. Fig. 6 is an enlarged detail plan view of a portion of the carrier and ejector. Fig. 7 is a detail side elevation of the said carrier and ejector. Fig. 8 is a cross-section of one of the carrier-guides, and Fig. 9 is a broken detail perspective view of a strip of veneer adapted to be cut into staves.

The machine is provided with a suitable frame 10, which has journaled in it a revoluble cutting-drum 11, this, as illustrated, being hollow, and the drum is carried by a shaft 12, 75 which may be driven in any suitable manner. Around the face of the drum are knives 13, which are arranged in pairs, the knives of each pair being oppositely curved, as best illustrated in Fig. 4, and thus a stave cut between a pair of knives will be widest in the middle and will taper toward its ends. These knives may be fastened to the drum in any convenient way or may be formed integral with the drum, but, as shown, they are dovetailed into the face of the drum. (See Fig. 1.)

Opposite the cutting-drum 10, and preferably above it, is a bearing-drum 15, which is provided with grooves 14 to register with the knives 13, and the drum 15 is carried by a shaft 16, which is journaled in the frame 10 and is driven by gear-wheels 17, 18, and 19, connecting with gear-wheels 20 on the main shaft 12; but it is of course understood that any of the moving parts of the machine may be driven in any customary manner.

The staves which are severed from a strip by the knives 13 have a tendency to stick between the knives, but they are forced outward by the cross-bars 21 of a carrier and ejector 22; and as these cross-bars lie flat against the face of the drum at the time the cutting takes place the staves are cut so as to lie on the cross-bars, and as the cross-bars

travel tangentially to the drum and eventually move outward from between the knives it will be seen that the staves will be lifted from the knives and carried away by the carrier. These cross-bars 21 are connected by links 23, which thus form an endless carrier, and the cross-bars are also connected loosely by chains 23^a, which prevent them from tipping over and so interfering with the work 10 of the machine.

The upper portion of the carrier travels in an almost level position through the machine and over the drum 10, and the carrier is guided and moved by sprocket-wheels 24, which are 15 arranged triangularly in the machine, as shown clearly in Fig. 1, one pair of these sprocket-wheels having their shaft provided with gear-wheels 25, which connect by gear-wheels 26 with gear-wheels 20 on the shaft 20 12. It is necessary to have the carrier made and timed so that the cross-bars 21 shall accurately register with the spaces between the knives 13.

To guide the carrier and enable the cross-bars to move with necessary precision over the drum 11, the carrier has journaled on its sides rollers 27, which run on angle-guides 28, these being secured to the frame 10 at opposite ends of the drum 11 and being curved 30 slightly upward, as shown clearly in Fig. 1. The carrier will work without the angle-guides 28, but the latter are preferably used. It will be noticed that the cross-bars 21 will not eject the waste material which is cut from the veneer and which will lie in the small spaces 35 13^a between the knives 13, and to provide for ejecting this material the construction described below and shown in detail in Fig. 3 is used.

40 Between alternate pairs of knives 13 and opposite the spaces 13^a are the waste or supplemental ejectors 29, which lie normally flat against the face of the drum 11, but which at necessary points are forced outward, so as to 45 carry out the waste material and bring it into contact with brushes to be presently described, which remove the said material from the drum. Each ejector 29 (see Fig. 3) is carried by arms 30, which at their inner ends 50 are pivoted to a suitable support on the drum 11, and the arms have a sliding connection, as shown at 32, with a rod 33, which extends outward endwise from the drum 11 and has at its outer end a truck 34, running in a hollow cam-track 35, which is fast on the frame 10 and is circular, so that the trucks 34 may readily follow it. The groove in the track 35 is carried in and out with relation to the drum 11, as shown by dotted lines in Fig. 3, and it 55 will be seen by reference to said figure that when the trucks 34 are forced inward the rods 33 and arms 30 are moved inward and the ejectors 29 drawn in against the face of the drum 11; but when the trucks 34 are moved 60 outward, as shown at the bottom of Fig. 3, the reverse movement takes place, and the ejectors 29 are moved outward nearly to the

edges of the knives 13, and the material on the ejectors is thus carried out to a point where it may be conveniently removed, as presently 70 described.

At opposite ends of the machine and opposite the place where the ejectors 29 move outward, which point is preferably on the under side of the drum 11, are revoluble brushes 36, 75 which are preferably of metal, and the faces of which are preferably roughened so that they will readily engage the waste material carried outward by the ejectors 29. These brushes 36 turn toward the ends of the machine and they engage the said waste material and throw it outward from between the knives 13. The brushes 36 are carried by shafts 37, 80 which are driven by beveled gears 38 and 39, (see Fig. 5,) the latter of said gears being carried by the shaft 40, which is journaled on the frame 10 and has a suitable driving-pulley 41. The outer ends of the shafts 37 are journaled in arms 42, which are in turn journaled on the shaft 40, and the inner ends of the shafts 37 90 are journaled in boxes 43 on a cross-rod 44, which is adjustable up and down in the slots 45 of the arms 46 on the machine-frame 10, (see Fig. 1,) and it will thus be seen that the brushes may be moved in and out with relation to the drum 11, so as to bring them into 95 position to engage the waste material already referred to, while they may be held in any desired position by tightening the nuts 47 on the ends of the rod 44. 100

I do not confine myself to this particular means of adjusting the brushes 36, nor even to the use of the brushes 36, as with many kinds of material the ejectors 29 will throw out the waste material without using the 105 brushes.

It will be noticed that the journals of the bearing-drum 15 and of one side of the sprocket-wheels 24 are adjustable; but I have not referred to this fact particularly, as no novelty 110 is claimed for it.

The operation of the machine is as follows: A strip 48 (see Fig. 9) of veneer is turned from a log with the croze-groove 49 in the strip near its opposite edges, and with the edges beveled 115 in the usual manner, as shown at 50. This strip is fed into the machine at one side upon the carrier and ejector 22, and as it passes between the drums 11 and 15 the strip is cut by the knives 13 into staves, which are carried 120 outward from between the knives by the ejecting cross-bars 21, and the staves are dropped at the back end of the machine. The waste material cut between each pair of staves is ejected from between the knives by the ejectors 29 and the mechanism already described 125 in detail, and thus it follows that a continuous strip of veneer may be fed into one side of the machine, while formed staves drop continuously from the back side of the machine. 130

It is evident that this method provides for rapidly cutting a fine quality of staves, and it is also apparent that the shape of the staves may be changed at will by changing the shape

of the knives 13, and hence that any ordinary staves—such as barrel, firkin, tub, and analogous staves—may be formed by my machine and method.

5 Having thus described my invention, I claim as new and desire to secure by Letters Patent—

1. A stave machine, comprising a revoluble cutting drum having circumferential knives, a bearing for the knives, and a flexible belt-like carrier moving tangentially across the face of the drum, the said carrier having cross bars to fit between the knives and serve as ejectors, substantially as described.

15 2. In a stave machine the combination with the revoluble cutting drum and its peripheral knives, of the flexible belt-like carrier traveling across the face of the drum and provided with cross bars entering between the knives 20 of the drum, the rollers journaled on the carrier, and the guides at the drum ends to support the rollers, substantially as described.

25 3. In a stave machine the combination of the cutting drum, the peripheral knives, the flexible belt-like carrier traveling across the face of the drum and provided with cross bars entering between the knives, and means as the chains 23^a, for preventing the tipping of the cross bars, substantially as described.

30 4. A stave machine, comprising a revoluble cutting drum having peripheral knives arranged in pairs, a carrier traveling across the face of the drum and provided with cross bars extending between alternate pairs of knives

to serve as ejectors, and a second series of 35 supplemental ejectors arranged between the end portions of alternate pairs of knives to eject material from between the said knives, substantially as described.

5. In a machine of the kind described, the 40 combination with the revoluble cutting drum and its peripheral knives, of the moving ejectors between the knives, pivoted arms supported on the drum and carrying the ejectors, and a cam mechanism to move the arms and 45 ejectors, substantially as described.

6. The combination with the revoluble cutting drum having peripheral knives, and the radially movable ejectors between the knives, of the swinging arms pivoted to the drum and 50 to the ejectors, the longitudinally movable rods connected to the arms, and a cam mechanism for moving the rods in and out, substantially as described.

7. The combination with the cutting drum 55 having peripheral knives, of the radially movable ejectors between the knives, the arms pivoted to the drum and to the ejectors, the rods secured to the arms and projecting from the ends of the drum, and means, as the circular cam tracks and the trucks on the rods, for actuating the arms and ejectors by the turning of the drum, substantially as described.
